United States Patent Office

Des. 178,357
Patented July 31, 1956

178,357

PAPER CLIP

Richard G. Galef, New York, N. Y., assignor to The Ravenware Company, Inc., New York, N. Y.

Application July 13, 1955, Serial No. 36,955

Term of patent 7 years

(Cl. D74—2)

Fig. 1 is a top view; Fig. 2 is a side view; and Fig. 3 is a bottom view of a paper clip showing my new design.

I claim:

The ornamental design for a paper clip, substantially as shown.
